DESIGN FOR A COMBINED HANDBAG AND COMPACT

Ida Jolles, New York, N. Y.

Application July 25, 1940, Serial No. 93,921

Term of patent 3½ years

To all whom it may concern:

Be it known that I, Ida Jolles, a citizen of the United States of America, residing in New York city, county of New York and State of New York, have invented a new, original, and ornamental Design for a Combined Handbag and Compact, of which the following is a specification, reference being had to the accompanying drawing, forming part thereof, wherein,

Figure 1 is a front view of a combined handbag and compact showing my new design.

Figure 2 is an end elevational view thereof.

Figure 3 is a top plan view of Figure 1.

The rear of the combined handbag and compact is substantially plain in appearance.

I claim:

The ornamental design for a combined handbag and compact, as shown and described.

IDA JOLLES.
